UNITED STATES PATENT OFFICE

HENRY H. MORETON, OF SANTA MONICA, CALIFORNIA, ASSIGNOR OF ONE-THIRD TO
O. B. ENGLISCH, OF CHICAGO, ILLINOIS, AND ONE-THIRD TO CHARLES F. CRAIG, OF
LOS ANGELES, CALIFORNIA

METHOD OF RECLAIMING CONTAMINATED OILS

Application filed February 18, 1928. Serial No. 255,406.

This invention is a method of treating contaminated oils, such as crank case oil and the like so that the said oils may be reclaimed and rendered fit for reuse.

5 One of the objects of the invention is to provide for an effective elimination of the mechanical impurities which are suspended in used oils, such for instance as crank case oils. A further object is to provide for effect-
10 ually removing any gasoline or similar volatile content. A further object is to effectually filter the oil in such manner that a maximum elimination of the impurities may be obtained within a minimum period of time, 15 and without the necessity of employing expensive and cumbersome apparatus.

The invention will be hereinafter fully set forth and particularly pointed out in the claims.

20 In the accompanying drawings:—

Figure 1 is a side elevation and Figure 2 is a front elevation illustrating a form of apparatus for carrying out the invention, it being understood however, that said apparatus is merely illustrative in character, and that the method herein involved is not limited thereto. Figure 3 is a detail sectional view illustrating the filter. Figure 4 is a similar view illustrating the vaporizing ap-
30 paratus.

Referring to the drawings, 10 designates a frame work in the top of which is supported a tank 11 for receiving the oil to be treated. Said tank is provided with a suitable filling opening normally closed by a removable plug 12. Leading from the bottom of said tank is a discharge pipe 13, controlled by a valve 14, said pipe discharging into a vaporizing chamber 15 suitably supported in said frame.

40 Said vaporizing chamber 15 consists of a trough-like casing in which the oil may be heated in any desired manner. It is preferred, however, to employ one or more electrical heating elements conventionally illustrated at 16, supported by the head 17, and extending longitudinally of the casing at a level to be submerged in the oil. Current may be supplied to the heater through an electric cable 18 connected with a source of 45 electricity (not shown). The top of the

casing 15 is normally closed by a hood 19, so as to direct the volatile constituents of the oil to a flue 20, by means of which said volatile constituents may be conducted away, preferably to a suitable condenser (not 55 shown).

The heater element 16 may be constructed to raise the temperature of the oil to any desired degree, preferably not exceeding 300° F. It has been found in practice that if the oil is heated to a temperature of approximately 260° F., and uniformly maintained at that temperature for a short time, the gasoline and other similar volatile diluents will be fully driven off, because the combination of gasoline and similar volatile hydrocarbons with the oil appears to be merely a mechanical mixture which is readily broken up at the named temperature. 60

In order that the flow of the oil through 70 the vaporizing chamber may be controlled, so as to subject it to the desired heating temperature for a long enough period to insure separation of the volatile contents, a thermostatic valve V is employed. Said valve 75 consists of a tube 22 of brass or similar metal, mounted in a bushing 23, screwed into an end wall of the chamber 15 so as to submerge the tube within the oil contained within the chamber. Said tube is provided with perforations 24 to permit oil to flow into the tube and the other end of the tube is closed by a cap 25 provided with an outlet opening 26. The flow of oil through said opening is controlled by means of a rod 27 of steel or other metal having a different expansion from that of the tube 22, said rod being supported at its inner end by the inner end of the tube, as indicated at 27a. It is to be understood that 80 while the oil is cold or below the temperature for which the thermostat is set, the opening 26 is closed by the rod 27 in a manner to prevent the outflow of oil from said heating chamber. As soon as the temperature of the oil rises to the desired degree, the rod is withdrawn from the opening 26 and the oil is free to flow therethrough. The cap 25 has a threaded engagement with the end of the tube 21 so that it may be adjusted with re- 85

90

95

100

spect to the rod to vary the range of movement of the rod 26 with respect thereto.

- The oil is discharged from the heating chamber 15 through a delivery pipe 28, having its discharge end located above a filling opening 29 in the top of a storage chamber 30, so that the oil will be discharged into said chamber 30. The opening 29 may be closed by a suitable removable plug 31. Leading 10 into the top of the tank 30 is a pressure supply pipe 32 controlled by a valve 33, and connected with a suitable source of pressure (not shown), such as an air compressor or the like.
- 15 Located in a plane below the tank 30 is a filter F, which consists of a casing 35 having a flange 36 at its lower end, to which are secured a perforated plate 37 and sheets 38 of filtering material. Said filter casing is 20 connected with the storage tank 30 by means of a pipe 39, controlled by a valve 40. The filter is also provided with a blow off valve 41. The filtering operation is greatly facilitated by raising the temperature of the oil 25 while being filtered, and for this purpose the filter casing 35 is provided with heating means such as an electrical heater 42, similar to the heater employed in the vaporizing chamber 15.
- 30 In order to hasten the filtering operation, and facilitate the separation of the mechanical impurities from the oil, the filter chamber is provided with a bed 43 of calcareous cement. It is preferred to use finely powdered gypsum for this purpose, because this material is more easily handled and appears to have a very strong affinity for carbon particles and other mechanical impurities suspended in the oil. But any other calcareous 35 cements such as Portland cement, and natural cement for instance, will serve. In practice, the gypsum may be deposited upon the filter cloths 38 and spread thereover in a layer of the desired thickness. Or, if desired, 40 the gypsum may be mixed with other substances such as acid treated filter clay, or a powdered dry alkali, such as soda ash. Or the gypsum alone or mixed with either of the other substances above mentioned may be 45 mixed with clean oil to form a paste and placed in the filter chamber. The result is that irrespective of the form in which the calcareous material is employed, it quickly forms an even surface under pressure, and 50 perfect filtering starts at once.

In operation, the oil to be treated is introduced into the tank 11 and allowed to flow therefrom into the vaporizing chamber 15. When the oil in the said vaporizing chamber 55 has reached the temperature at which the thermostat will operate, the discharge valve will open and the oil will flow out of said chamber into the storage tank 30. In the meanwhile, the heater element will have 60 raised the temperature of the oil sufficiently

to cause the volatile diluents to pass upwardly into the hood 19 and flue 20. When the tank 30 has been filled, the flow of oil from the tank 11 is arrested by means of the valve 14, and the inlet opening 29 of the tank 30 70 is closed by the plug 31. The valve 33 is then opened and pressure is introduced through the pipe 32 into the tank 30, thereby forcing the oil through the pipe 39 into the filter chamber 35, the valve 40 being 75 opened to permit this flow. As the oil is forced through the bed 43 of calcareous material, the carbon particles are attracted to said material, but the oil is permitted to flow through under pressure into a suitable container located below the filter, the filter cloth also performing the usual functions of such material, i. e. retaining the mechanical impurities which are not attracted by the calcareous material. 80

The advantages of the invention will be readily understood by those skilled in the art to which it belongs. For instance, a very important advantage is that contaminated oils, such as crank case oil for instance, may be so purified in a short space of time that it is capable of reuse in any capacity for which it was originally intended. It will also be noted that the process is an exceedingly simple and inexpensive one, being economically 85 carried out because it avoids the use of highly expensive cumbersome apparatus.

No claim for the apparatus is made herein because said apparatus is made the subject of a separate application filed February 18, 100 1928, Serial No. 255,405.

Having thus explained the nature of the invention and described an operative manner of constructing and using the same, although without attempting to set forth all of the forms in which it may be made, or all of the forms of its use, what is claimed is:—

1. A method of reclaiming contaminated lubricating oils comprising providing a fixed bed of calcareous substance possessing the 110 characteristic of attracting to it mechanical impurities suspended in the oil, and causing the oil to filter through said bed.

2. A method of reclaiming contaminated lubricating oils comprising providing a fixed 115 bed of a calcareous substance possessing the characteristic of attracting to it mechanical impurities suspended in the oil, and heating the oil in the vicinity of said bed during the filtration.

3. A method of reclaiming contaminated lubricating oils comprising first raising the temperature of the oil to remove any volatile diluents which may be carried thereby, providing a fixed bed of calcareous substance 120 having the capability of attracting to it mechanical impurities suspended in the oil, and causing the oil to filter through said bed.

4. A method of reclaiming contaminated lubricating oils comprising first heating the 130

oil to remove any gasoline which may be suspended therein, providing a fixed bed of a calcareous substance possessing the capability of attracting to it mechanical impurities suspended in the oil, and causing the oil to filter through said bed.

5. A method of reclaiming contaminated lubricating oils comprising providing a normally stationary, paste-like filter bed which includes gypsum as a constituent so that mechanical impurities suspended in the oil will be physically attracted to said filter bed, and causing the oil to filter through said bed.

10 6. A method of reclaiming contaminated lubricating oils comprising passing the oil through a normally stationary paste-like filter bed consisting of a calcareous substance having the capability of physically attracting mechanical impurities suspended in the

15 oil.

7. A method of reclaiming contaminated lubricating oils comprising bringing the oil into a normally fixed bed of a finely divided calcareous cement possessing the quality of 20 mechanically attracting to it carbon particles suspended in the oil, and applying pressure to the oil to force it through said bed.

In testimony whereof I have hereunto set my hand.

30 HENRY H. MORETON.
